UNITED STATES PATENT OFFICE.

MAURICE MATHY, OF FLEMALEE GRANDE, BELGIUM.

METHOD OF GRINDING GLASS STOPPERS.

1,232,465.

Specification of Letters Patent. Patented July 3, 1917.

Application filed May 18, 1915. Serial No. 28,952.

To all whom it may concern:

Be it known that I, MAURICE MATHY, a subject of the King of Belgium, residing at Flemalle Grande, Belgium, 28 Rue 5 Léopold, have invented certain new and useful Improvements in Methods of Grinding Glass Stoppers; and I do hereby declare the following to be a full, clear, and exact description of the invention, such as will enable others skilled in the art to which it 10 pertains to make and use the same, reference being had to the accompanying drawings, and to letters or figures of reference marked therein, which form a part of this 15 specification.

The present invention relates to an easy and economical method of grinding glass stoppers in such a manner that perfect stoppering and adhesion of the stopper to the 20 bottle neck are attained.

This method consists in grinding each stopper by means of the neck of the bottle to which the stopper must be secured, said bottle neck having previously been completely 25 ground by any suitable means and abrading agent. By rotating the stopper at a high speed and at the same time driving it in the bottle neck, it is possible to have the stopper ground by the action of the rugosity of 30 the previously ground neck; besides, the stopper is made to suit exactly the neck and no abrading agent is required.

When this method is used, the stopper must be secured to the end of a rotary shaft 35 and the present invention also relates to practical means for securing the stopper. This means consists in an india-rubber block provided on the end of the shaft and in which is created an axial hollow adapted to 40 take in the stopper's knob in such a manner that the edges of the cavity cover the lower part of the knob. By these means, the stopper can be put in position very quickly; the stopper is sufficiently secured to the rotary shaft as by a ball and socket or universal joint allowing the stopper to lean and to center exactly in the bottle neck.

The drawings show by way of example, a side view, partly in section, of a preferred 50 embodiment of the invention.

The machine comprises a horizontal shaft 1, journaled in bearings 2 forming parts of a frame 3, and driven at the required speed by means of a step-pulley 4. The shaft 1 55 terminates in a square rod 5 on which the

stopper-carrier 6 is secured; this stopper-carrier is provided with a housing 7, prismatical in shape, adapted to contain an india-rubber or the like block 8. In this block and in a line with the axis of the shaft 1, a cavity is provided, the shape of which is chosen so as to suit the shape to the knob 9 of the stopper 10. The edges 11 of this cavity cover the lower part of the knob 9 in such a manner that the knob can only be forced 60 into the cavity owing to the elasticity of the rubber block; it is then secured in the cavity by said elasticity.

When the stopper to be ground has been secured to the rotary shaft in the hereinbefore described manner, the workman takes the bottle 12 that the stopper must fit, the neck 13 of which has been previously ground completely by means of any suitable abrading agent. While the stopper 10, driven by 70 the shaft 1, is rotating on its own axis at a high speed, the workman brings the bottle nearer to the stopper 10 in such a manner that the stopper gradually gets into the mouth 13. The stopper is ground in this 75 manner, without using any abrading agent, by the mouth 13 itself which remains always rugous after grinding. The workman puts an end to the operation when the stopper fits exactly the mouth 13. 85

It must be noted that the stopper is held exactly centered by the rubber block 8 owing to the high speed rotation. The knob 9 is however allowed to move slightly in the cavity of the block 8, like the ball of a ball 90 and socket joint; thus the stopper can remain in the axis of the mouth of the bottle held by the workman.

What I claim is:

In apparatus for grinding glass stoppers, 95 the combination of a rotary shaft, a housing at the end of said shaft, a block of elastic material in said housing provided with a hollow interior having a contracted opening or neck portion leading thereto which is 100 adapted to engage around the stopper beneath the head thereof when the latter is inserted into the hollow interior of the flexible block.

In testimony whereof I affix my signature 105 in presence of two witnesses.

MAURICE MATHY.
